WAVEGUIDE SWITCH DEVICE

Richard M. Walker, Boston, Bernard D. Berkowitz, Waltham, Arthur A. Blaisdell, Natick, and Vincent J. Mistretta, Framingham, Mass., assignors to Microwave Associates, Inc., Burlington, Mass., a corporation of Massachusetts

Filed Dec. 29, 1958, Ser. No. 783,520

5 Claims. (Cl. 333—98)

The field of this invention is that of waveguide attenuators and relates, more particularly, to waveguide switches or shutters for opening and closing a waveguide passage with regard to the transmission of microwave energy.

A typical, although by no means the only use of waveguide switches, in that instance commonly referred to as shutters, is in radar duplexer systems employing transmit-receive (TR) or anti-transmit-receive (ATR) tubes. During normal operation of all systems of this type which employ gas discharge TR tubes, the highly sensitive point-contact crystal detector of the system is protected by the so-called "keep-alive" in the TR tube which continuously supplies electrons in a small resonant gap which, due to these electrons, will fire and electrically shunt the waveguide at comparatively low power levels which cannot damage the crystal detector therebehind. However, when the installation is inoperative, with its power turned off, the keep alive is inoperative and the gap will fire only at a power level of much higher magnitude than when the system is operative. In this case the TR tube, being unfired, will pass power at levels sufficiently high to damage the sensitive detector. Such power may come, for example, from the transmitter of a nearby operating radar set feeding into the antenna of the inoperative set to be protected.

It has been proposed to provide additional protection for the crystal detectors of such systems by mechanically shorting the waveguide transmission line when power is turned off, either by way of vanes inserted across the waveguide or by providing the resonant gaps with structures for mechanically bridging them. Such provisions are not satisfactory from the point of view of reliability because they require large linear motion of the shorting structure and because they rely on metallic contacts for their electric performance. Linear motion is objectionable in any equipment which must withstand shock and vibration, and because it requires relatively large operating forces. Furthermore, devices which depend for their operation on linear motion of one component relative to the remainder of the device will undergo changes in operating characteristics when subjected to acceleration at various angles to the direction of the linear motion. Metallic contacts are objectionable for similar reasons and because they are subject to wear which destroys the electrical characteristics of the device, and because the contact surfaces will acquire deformations causing the device to stick in open or closed position.

Objects of this invention are to provide a waveguide shutter which essentially eliminates the above defects by minimizing the force required to operate the device and the possibility of wear, to provide such a device which due to its very small motion permits fast operation and also minimizes force, impact and wear, to provide such a device which eliminates the use of metallic contacts for establishing its electrical function, and to provide a waveguide shutter whose characteristics are not appreciably affected by acceleration in any direction, such as, for example, might be caused by shock and vibration.

Other objects are to provide waveguide shutters, which when in closed position, will effect substantially complete reflection of microwave energy and will allow only neg-

2

ligible leakage of the microwave energy through the waveguide, and which, when in open position, will permit transmission of microwave energy through the switch with minimum insertion loss, to provide a shutter whose characteristics are not adversely affected by shock or vibration; which is fast-acting, not subject to excessive wear, and which requires a minimum of power for its actuation, and to provide a shutter system which is simple, compact, fully reliable and efficient, and which can be easily adapted for insertion in various types of waveguide transmission lines.

A brief summary of the nature and substance of the invention and of some of its main aspects is as follows:

Systems according to the invention comprise, for attachment within a waveguide section of a transmission line: a vane, means for rotatably mounting the vane transversely in a waveguide section for rotation between a closed position across the passage when the shutter will reflect substantially all microwave energy within the waveguide, and an open position parallel to the passage when the shutter will permit the transmission through the switch of substantially all microwave energy entering the waveguide, and actuating means for rotating the shutter between open and closed positions.

In the herein described preferred embodiment of this invention the actuating means are electromagnetic and, in a specific, particularly practical aspect, comprise, a permanent magnet rotatable with the shutter, and an electromagnet disposed adjacent to the walls of the waveguide section such as to align the shutter magnet with the field of the electromagnet when the electromagnet is energized, causing the shutter to rotate between closed and open positions, a permanent biasing force such as spring means being utilized for returning the shutter to normal position when the electromagnetic field is withdrawn.

In the preferred embodiment of this invention, the shutter comprises a thin vane of a configuration similar to but slightly smaller than the cross-section of the waveguide passage and has axial pivots integral therewith for rotatably mounting the shutter in low friction bearings disposed in the center of opposite waveguide walls. In alternative embodiments, the vane is provided with one or more irises resonant with the capacitive or inductive gaps existing between the vane and the waveguide when the switch is in closed position, these gaps providing mechanical clearance for rotation of the vane within the waveguide section passage, thereby increasing the microwave attenuation effected by the switch. In other alternative embodiments, the vane edges are provided with dielectrically-filled slots to provide a filter section in the gaps between the vane and the waveguide when the switch is in closed position; these filter sections also increase the microwave attenuation effected by the switch.

In another aspect of the invention, lumped impedances are provided near opposite vane edges in the form of metallic bodies or buttons adjacent the pivots of the vane at the guide walls, these buttons constituting matching reactances for eliminating the reactive mismatch resulting from the vane in open position.

These and other objects, aspects of novelty, and details of construction will appear from the following description of a practical embodiment with several modifications thereof.

The description of these embodiments refers to drawings in which

Fig. 1 is an exploded isometric view of the waveguide switch according to this invention;

Fig. 2 is a side view of a waveguide shutter according to this invention;

Fig. 3 is a section on line 3—3 of Fig. 2;

Fig. 4 is a section of line 4—4 of Fig. 3;

Fig. 5 is a section on line 5—5 of Fig. 3;

Figs. 6, 10, 14 and 18 are partial views of alternative embodiments of the shutter vane according to the invention shown as they would appear in closed position looking into a waveguide;

Figs. 7, 11, 15 and 19 are sections on the correspondingly numbered lines of Figs. 6, 10, 14 and 18;

Figs. 8, 12, 16 and 20 are partial views of the shutter of Figs. 6, 10, 14 and 18 respectively, shown as they would appear in open position looking into a waveguide; and

Figs. 9, 13, 17 and 21 are equivalent electric circuit diagrams of the shutters of Figs. 6, 10, 14 and 18 respectively, when in closed position.

Referring to the drawings, 1 indicates a waveguide shutter assembly according to the invention, shown here adapted for insertion between the sections 2 and 3 of a conventional rectangular waveguide transmission line. The shutter is connected in the transmission line in conventional manner, here by the flange connectors, 4 and 6, as shown. The arrow *w* indicates the direction of flow of microwave energy through the waveguide.

The shutter assembly includes a rectangular waveguide section 7 comprising the broad webs 8 and 9, which correspond to the broad walls of the waveguide sections 2 and 3, and the narrow webs, 11 and 12, which correspond to the narrow walls of the waveguide sections 2 and 3. The waveguide section 7 is constructed of the usual waveguide material such as brass or aluminum.

The web 11 has a central aperture 14 to receive the bearing 16, preferably a ball bearing as shown, a shoulder 17 being provided for properly positioning the bearing. The web 12 has a similar aperture 18 and shoulder 19 for receiving and positioning the bearing 21.

The shutter proper 22, as shown in Figs. 1 and 3, is formed by a thin, rectangular, metallic vane 23 of slightly smaller dimensions than the waveguide passage 13. Cylindrical buttons, 24 and 26 are coaxially mounted on the vane on its longitudinal axis and have axially threaded bores 30. An axial pivot screw 27 is locked in threaded engagement with the button 24, and a second axial pivot screw 28 is similarly locked in threaded engagement with the button 26. Sleeves 29 and 31 are fitted over the screws 27 and 28 respectively, for properly positioning the vane 23 between the bearings 16 and 21, equally spaced from the waveguide webs 11 and 12.

The second pivot screw holds a permanent magnet 32, in fixed relation to the shutter vane 23, by the screw head 33, for rotation as a unit. The magnet has a flattened side 34 and is positioned on the screw 28 so that its pole axis as indicated in Fig. 2, normally extends parallel to the direction of flow of microwave energy through the shutter assembly and transversely of the broad faces of the vane 23. A stop in the form of a pin 36 projecting above the bearing 16, is so positioned and dimensioned that rotational movement of the magnet 32 is confined with a 90° arc. The spiral spring 37 engages the web 12 and the axial pivot screw 27 for biasing the vane 23 to the position shown in Fig. 3 whereby the magnet 32 will abut the stop 36 as shown in Fig. 2. The vane 23 will then be disposed within the passage 13 transversely of the direction of flow of the microwave energy therethrough. It will be evident that the magnet can be rotated away from the stop 36 until the opposite end of the magnet face 34 abuts the stop and that such motion corresponds to a 90° rotation of the vane 23 moving it to a position within the passage 13 parallel to the flow of microwave energy therethrough. The plate 37.1 and the screw 37.2 serve to hold the bearing 21 in place and the screw 37.2 at the same time anchors one end of the spring 37. The other end of the spring is staked to the spring collar 37.3, which in turn is held against the sleeve 29 by the head of the pivot screw 27.

At either end of the waveguide passage 13 the webs 8, 9, 11, and 12, which define the passage 13, meet in

laterally extending flanges 38 and 39 which form a rectilinearly peripheral groove 41 as shown in Figs. 2, 3, 4 and 5. The core piece 42, notched as at 43 to fit over the web 12 and grooved as at 44 to provide clearance

- 5 for the spring 37, is fixed within the rectilinear groove 41 adjacent the web 12. Series connected field coils 46.1 and 46.2 wound on cylindrical core pieces 47 are mounted within the rectilinear groove 41, one adjacent each of the webs 8 and 9 respectively, and are fixed to the core piece 42 by the screws 48. The core pieces 49 and 51, notched as at 52 and 53, respectively, to fit the web 11, are mounted within the rectilinear groove 41 adjacent the web 11 to provide the gap 54 therebetween, and are joined each to a core piece 47 by a screw 56. 15 Bores 57 extending through the waveguide flanges 38 and 39 and through the core pieces 42, 49 and 51, are provided for fastening the waveguide switch 1 within a waveguide transmission line.

In this manner an electromagnet is provided for establishing a magnetic circuit comprising the core pieces, 20 42, 47, 49 and 51, directed across the gap 54, and capable of rotating the permanent magnet 32 therein to the extent permitted by the stop 36.

- A non-magnetic cover 59, held to core pieces 49 and 25 51 by the screws 61 and having a sealing gasket 62, closes the gap 54. The coils, 46.1 and 46.2 are confined in potting compound 63 which fills the groove 41 adjacent the webs 8 and 9, the nuts 70 being encased in said potting of coil 46.1 to receive the screws 66. Terminals 64 30 for the leads 65 from the coils 46.2 as shown in Fig. 3, are fastened to the switch device by the screws 66. The nuts 70 are electrically connected internally to the ends of the windings of 46.1. For the sake of simplicity this is not illustrated in the drawings. The core piece 35 42 is provided with an external groove 67 for receiving and protecting the leads 65.

The operation of devices according to the invention as exemplified by the above-described embodiment is as follows.

- 40 It will be readily understood that a waveguide switch according to this invention, within a waveguide transmission line as shown in Fig. 2, for example within the transmission line to the receiver crystal in conventional radar equipment, will have its vane 22 normally biased into the position transversely of the waveguide passage 13 by the spring 37 as shown in Figs. 3 and 4 and will therefore reflect substantially all microwave energy directed towards it within the waveguide section 2. Thus the shutter will protect the receiver crystal of the radar set, while it is in power-off condition, from injurious exposure to 45 random high-power R.F. signals such as might be emitted by other radar equipment operating in the vicinity. When the radar set incorporating the shutter is placed in operative condition with the TR tube "keep alive" on, the shutter is rendered ineffective by connecting the terminals 64 to a D.C. source with suitable switching apparatus. The coils 46 will thus be excited and will establish a magnetic field across the gap 54 which will rotate the magnet 32 into alignment therewith against the bias of the spring 37 to the extent permitted by the 50 stop 36, thereby rotating the shutter 22 to a position parallel to the waveguide passage 13. In this position, the shutter will permit normal operation of the radar set. The following favorable mechanical conditions will 55 prevail at closed and open positions and during movement 60 from one to the other.

The shutter according to the invention has a very short and positive motion and is therefore fast-acting, and it will not be subject to injury or disalignment when exposed to shock or vibration. It will also be noted that its operation 70 in ball bearings minimizes the possibility of wear and the force required for operation. Furthermore, the shutter operation is not dependent upon the making and breaking of metallic electrical contacts within the switch, the vane being always spaced from the waveguide walls. 75 This feature also eliminates possibilities of wear and fur-

ther reduces the power required for actuation. This shutter is a dynamically and statically balanced structure which will retain its operating characteristics even when the switch device is accelerated in any direction. Thus, unlike shutter devices which are not so balanced, this device is particularly useful in high speed aircraft and missiles.

With regard to electrical operating conditions, the leakage in closed position and the insertion loss in open position are of primary importance; these conditions are optimally favorable in devices constructed according to the present invention for the following reasons.

When in closed position as shown in Figs. 3 and 4, the shutter vane presents a short circuit across the waveguide, reflecting essentially all the power. As indicated above, this is the normal position of a shutter used for the protection of crystal detectors in inoperative radar systems. In an ideal construction, the leakage of the closed shutter should be zero. The leakage in structures such as shown in Figs. 3 and 4 is determined by the capacitance between the vane edges and the broad waveguide walls. This capacitance can be made larger with a resulting decrease in leakage by making the gap indicated at "g" of Fig. 3 smaller, or by increasing the vane thickness indicated at "t" of Fig. 4. The possible increase in capacitance is controlled by practical manufacturing conditions and assembly tolerances. In previous practice, leakage has been controlled by metallic contacts and has been dependent upon cleanliness, wear and humidity. In the present invention, negligible leakage is permitted but this leakage does not vary with age or change in environmental conditions. The leakage value is less than 1% in power over the entire frequency range of the waveguide system in which the shutter is installed. Lower leakage values may be obtained over a narrower frequency range with shutter embodiments to be described below.

In open position, the vane is essentially reflectionless and therefore the R.F. signal passes freely through the shutter device to the receiver, without appreciable insertion loss. This favorable operation is materially aided by the provision of the above described buttons 24 and 26 for the following reason. In open position, the vane divides the waveguide into two equal guides each nearly half the full waveguide cross section. The open vane inevitably introduces a certain amount of capacitive and resistive mismatch. The capacitive reactance is largely matched out by the buttons 24 and 26 which constitute lumped inductances matching the vane section capacitive reactances. The resistive mismatch is negligible as will presently be shown below by actual performance data. The major contribution to the insertion loss of components of this type is reflected power which can be determined by VSWR measurements. The matching buttons are very effective in providing a very low VSWR over a wide frequency range, indicating practically zero insertion loss. One of the first models constructed according to the present invention, with buttons 24, 26 according to Figs. 3, 4 and 5, had the negligible insertion loss of less than 0.1 db over a 12% frequency range. The VSWR over the 12% frequency range was less than 1.06.

The above-described construction with the vane normally closed transversely across the waveguide, assumes a normally de-energized controlling magnetic motor. This manner of operation can be reversed by rotating the magnetic armature 32 on its shaft 28 to put it parallel to the vane. The shutter is then normally open with the motor de-energized which, when energized, will rotate the vane in opposite direction into closed position.

The alternative embodiments according to Figs. 6 to 21 illustrate vane constructions which can be used with shutters such as shown in Fig. 3, these alternative embodiments effecting even greater attenuation of microwave energy when the switch is in closed position, as compared to the simple vane of Fig. 3.

The vane 68 shown in Figs. 6 to 8 is provided with a rectangular iris 69 but is otherwise the same as the shutter

vane 23. This iris is selected to be resonant at a frequency considerably higher than operating frequency. In this case, the equivalent circuit, as shown in Fig. 9, includes iris inductance 69a and iris capacitance 69b as well as the gap capacitance 68a resulting from the gap required for mechanical clearance between the closed vane 68 and the broad waveguide web 8. The iris represents an inductive parallel circuit and at operating frequency this inductance is series resonant with the gap capacitance 68a thereby presenting a complete short circuit across the waveguide. This type of vane effects substantially complete attenuation, tests indicating leakage of less than 0.1% of the incident power over a 12% frequency range. In the open position, vane 68 causes insertion losses similar to those measured for the simple vane 23 according to Fig. 3.

The vane 71 as shown in Figs. 10 to 12 is provided with slots 72.1, 72.2 filled with dielectric material 73. Each slot represents a short choke section to provide a filter in each gap as shown by the equivalent circuit Fig. 13 wherein 72a are the gap impedances between the vane impedance 71 and the broad waveguide walls 8 and 9. The effective depth of the slots determines whether these impedances are inductive or capacitive and this effective depth and hence the type of impedance can be controlled by varying the dielectric constant of the material which fills the slots. Tests indicate that a slot of a depth approximately equal to $\frac{1}{6}$ of a guide wavelength has an inductive effect and that a slot of a depth approximately equal to $\frac{3}{3}$ of a guide wavelength has a capacitive effect; in either case, the electrical characteristics of this vane over a 12% frequency range are similar to that of the vane 68 according to Figs. 6 to 9.

The vane 74 shown in Figs. 14 to 16 has a single slot 76 filled with a dielectric material 77. Tests indicate that in this instance a slot depth slightly less than $\frac{1}{2}$ of a guide wavelength has a capacitive effect and increases the attenuating effect of the closed vane over a 12% frequency range to approximately that of the vane 68 of Figs. 6 to 8. Fig. 17 shows the reduced capacitances 76a existing in the gap between the vane 74 and the broad waveguide webs 8 and 9.

The vane 78 shown in Figs. 18 to 20 is provided with diaphragms 79 and 81 forming the inductive irises 82 and 83. These inductances 82a and 83a are adjusted to resonate with the capacitances 78a and 79a and 81a as indicated in Fig. 21, existing in the gaps between the vane 78 and the diaphragms 79 and 81 respectively, and the broad waveguide webs. The vane 78 as provided with the diaphragms 79 and 81 has an attenuating effect approximately equal to that of the vane 68 of Figs. 6 to 8.

From the above practical test results it will be evident that devices according to the invention provide substantially complete microwave attenuation when in closed position and permit substantially complete microwave transmission when in open position. It will also be evident that this device is suitable for use with various types of waveguide apparatus, such as for example the so-called short-slot hybrid or the folded magic tee, to perform functions such as that of an attenuator or of a rotary switch from one antenna to another, or of a variable power divider.

It will be further evident that certain features of the invention—such as the central suspension of the vane, the clearance between vane and guide section, and the mismatch eliminating buttons between vane and guide wall positions—did not necessarily have to be used with rectangular guides but have more general application.

It should be understood that the present disclosure is for the purpose of illustration only and that this invention includes all modifications and equivalents which fall within the scope of the appended claims.

We claim:

1. Waveguide switch apparatus comprising: a straight rectangular waveguide section of substantially uniform

internal cross section throughout its length; a substantially flat rectangular metallic shutter vane having a thickness which is a minor fraction of any internal cross-sectional dimension of said waveguide section, said vane being dimensioned in the length and width directions perpendicular to its thickness dimension effectively to fill the internal transverse cross section of said waveguide without touching any of the walls thereof; means for mounting the shutter vane for rotation within said guide section, about an axis of symmetry of the guide section and the vane, to each of two fixed positions, one of which is a closed position transversely of the guide section and the other of which is an open position parallel to the guide section axis; and metallic bodies of substantially cylindrical cross section permanently affixed to each narrow side edge of said vane concentric with the rotational axis thereof, each of said bodies presenting a substantially circular surface adjacent and spaced from the confronting narrow wall portions, respectively, of the waveguide section, said bodies being dimensioned and located to constitute axially symmetrical lumped inductance elements for matching the capacitive reactance across the waveguide section introduced by the vane in the open position.

2. Waveguide switch apparatus comprising: a straight rectangular waveguide section of substantially uniform internal cross section throughout its length; a substantially flat rectangular metallic shutter vane having a thickness which is a minor fraction of any internal cross-sectional dimension of said waveguide section, said vane being dimensioned in the length and width directions perpendicular to its thickness dimension effectively to fill the internal cross section of said waveguide without touching any of the walls thereof; means for mounting the shutter vane for rotation within said guide section, about an axis of symmetry of the guide section and the vane, to each of two fixed positions, one of which is a closed position transversely of the guide section and the other of which is an open position parallel to the guide section axis; and metallic bodies of substantially cylindrical cross section, each having a diameter which is of the order of half the dimension of said vane in said width dimension, permanently affixed to each narrow side edge of said vane concentric with the rotational axis thereof, each of said bodies presenting a substantially circular surface adjacent and spaced from the confronting narrow wall portions, respectively, of the waveguide section, said bodies being dimensioned and located to constitute axially symmetrical lumped inductance elements for matching the capacitive reactance across the waveguide section introduced by the vane in the open position.

3. Waveguide switch apparatus comprising: a straight rectangular waveguide section of substantially uniform internal cross section throughout its length; a substantially flat rectangular metallic shutter vane having a thickness which is a minor fraction of any internal cross-sectional dimension of said waveguide section, said vane being dimensioned in the length and width directions perpendicular to its thickness dimension effectively to fill the internal transverse cross-section of said waveguide without touching any of the walls thereof; means for mounting the shutter vane for rotation within said guide section, about an axis of symmetry of the guide section and the vane, to each of two fixed positions, one of which is a closed position transversely of the guide section and the other of which is an open position parallel to the guide section axis; metallic bodies of substantially cylindrical cross section permanently affixed to each narrow side edge of said vane concentric with the rotational axis thereof, each of said bodies presenting a substantially circular surface adjacent and spaced from the confronting narrow wall portions, respectively, of the waveguide section, said bodies being dimensioned and located to constitute axially symmetrical lumped inductance elements for matching the capacitive reactance across the waveguide section introduced by the vane in the open

position; the length of said waveguide section being only slightly greater than the dimension of said vane in said width direction, said waveguide section being fitted at each end with transversely outwardly extending flange means for attaching said waveguide section in a waveguide transmission line; and actuating means contained substantially entirely within the annular space outside said waveguide section bounded by said flange means for rotating said vane between each of said two fixed positions.

4. Waveguide switch apparatus according to claim 3 in which the actuating means comprises a shaft extending from the vane through the waveguide section; magnet core means arranged around the periphery of said waveguide section and having an air gap therein; coil means on said core means adapted to establish a magnetic field in said core means; permanent magnet armature means affixed to said shaft within said air gap; and biasing means connected between said waveguide section and said shaft urging the vane to rotate in one direction opposed to the direction in which said armature means is urged by said magnetic field when said core means is energized; whereby the vane can be rotated between said two positions by establishing and removing the field.

5. Waveguide switch apparatus comprising: a straight rectangular waveguide section of substantially uniform internal cross section throughout its length; a substantially flat rectangular metallic shutter vane having substantially flat edges and a thickness which is a minor fraction of any internal cross-sectional dimension of said waveguide section, said vane being dimensioned in the length and width directions perpendicular to its thickness dimension effectively to fill the internal transverse cross section of said waveguide without touching any of the walls thereof; means for mounting the shutter vane for rotation within said guide section, about an axis of symmetry of the guide section and the vane, to each of two fixed positions, one of which is a closed position transversely of the guide section and the other of which is an open position parallel to the guide section axis; metallic bodies of substantially cylindrical cross section permanently affixed to each narrow side edge of said vane concentric with the rotational axis thereof, each of said bodies presenting a substantially circular surface adjacent and spaced from the confronting narrow wall portions, respectively, of the waveguide section, said bodies being dimensioned and located to constitute axially symmetrical lumped inductance elements for matching the capacitive reactance across the waveguide section introduced by the vane in the open position; and an iris opening in said vane, resonant at a frequency which is high relative to the intended operating frequency of the waveguide, said iris inductance being resonant substantially at said operating frequency with the capacitance existing between the flat edges of the shutter vane and the adjacent wide walls of said waveguide section when the vane is in said closed position, whereby said vane in said closed position provides a substantially complete short circuit across said waveguide section at said operating frequency.
